UNITED STATES PATENT OFFICE.

WILLIAM C. TREGONING, OF HARTFORD, CONNECTICUT, ASSIGNOR, BY MESNE ASSIGNMENTS, TO PERKINS CORPORATION, OF HARTFORD, CONNECTICUT, A CORPORATION OF CONNECTICUT.

ELECTRIC-SWITCH CONTACT.

SPECIFICATION forming part of Letters Patent No. 783,652, dated February 28, 1905.

Application filed May 24, 1904. Serial No. 209,552.

To all whom it may concern:

Be it known that I, WILLIAM C. TREGONING, a citizen of the United States, residing at Hartford, in the county of Hartford and State of Connecticut, have invented a new and useful Electric-Switch Contact, of which the following is a specification.

This invention relates to the construction of spring-arm contacts which are adapted to receive the rotary or oscillating blades of turn-button or push-button snap-switches.

The object of the invention is to produce an efficient construction which is simple and cheap to manufacture and assemble.

15 The embodiment of the invention illustrated in the accompanying drawings has a tubular post that is attached to a supporting-plate and is provided with a binding-screw, also a pair of spring-plates which are stamped with flanged perforations and are applied flange to flange on a swaged portion of the post.

Figure 1 of the illustrations shows a side elevation of a contact that embodies the invention. Fig. 2 shows a plan of the same. Fig. 25 3 shows a vertical section of the contact. Fig. 4 shows a plan of one of the contact-plates, and Fig. 5 shows a section of one of the contact-plates.

The tubular post 1 of this contact is attached 30 in any convenient manner to the supporting-plate 2, which is adapted to be secured to the base of the switch. A binding-screw 3 extends into the opening through the post, so as to clamp the end of a circuit-wire that is thrust 35 therein.

In the manufacture of this contact it is preferred to swage both ends of the post into a hexagonal form; but of course the ends could be made square or octagonal, if desired. One 40 end is thrust through an opening in the supporting-plate and headed over, and on the other end the contact-plates are placed, and then that end is headed over.

The contact-plates 4 are the same shape and size. When these plates are formed, preferably a hexagonal perforation is punched in each and portions of the metal about the hole are stamped down, so as to form a flange 5, with an opening which fits the upper end of the post. These plates are placed on the angular end of the post with the flanges together, so that the plates are slightly separated, and their ends are bent down, so that the spring-arms 6 will grip the blade of the switch that is thrown between them. After the plates 55 have been placed on the angular end of the post the end is headed over to hold them in position. The flanges separate the plates sufficiently without the interposition of any washers, and the angularity of the openings through 60 the plates and the end of the post prevents the plates from turning on the post.

This contact is very simple to manufacture, for the ends of the post may both be swaged alike, and the plates are identical. The parts 65 are easy to assemble, for no washers are required.

The invention claimed is—

1. A switch-contact having a post with an angular end and plates with flanges and angular openings fitting the angular end of the post, substantially as specified.

2. A switch-contact having a post with an angular section at each end, a supporting-plate located on the angular section at one 75 end, and a pair of plates with flanges and angular openings located on the other angular end of the post, substantially as specified.

3. A contact-plate having contact-arms and an integral flange extending from one side, 80 and provided with an angular opening, substantially as specified.

WILLIAM C. TREGONING.
